UNITED STATES PATENT OFFICE.

JOSEPH BOUTEILLE, OF PARIS, FRANCE.

ELECTRIC INTERRUPTER.

1,333,202.

Specification of Letters Patent.

Patented Mar. 9, 1920.

Application filed December 18, 1917. Serial No. 207,763.

To all whom it may concern:

Be it known that I, JOSEPH BOUTEILLE, a citizen of the Republic of France, of 51 Rue Lacordaire, Paris, France, engineer, 5 have invented new and useful Improvements in Electric Interrupters, which improvements are fully set forth in the following specification.

This invention relates to apparatus for 10 mechanically interrupting electric currents between two electrodes, and is more particularly applicable to magnetos for the ignition of internal combustion engines. It has for its object to provide a simple apparatus which can run at relatively high 15 speeds with little wear either of the electric contacts or of the parts in movement.

According to this invention a spring mounted member or projection acted upon 20 by a cam and a spring mounted electric contact are supported separately, but are connected in their movement by an intermediate piece, such as a freely moving suitably guided rod. Preferably the projection 25 and the contact are mounted on two different springs which may be formed of a single blade or of a U shaped spring whose central portion is rigidly fixed.

The accompanying illustrative drawing 30 shows a front elevation of an apparatus made in accordance with this invention.

1 is a plate turning with the armature of the electric machine to which it is fixed; it carries on one side of its axis an electrically insulated metal piece 2 made fast 35 by a screw 3. A U shaped spring 4 is rigidly fixed to the metallic piece 2; the free ends of the spring support the fiber projection 5 (which receives its necessary movement 40 from one or more cams 6 fixed to the frame of the machine) and the electric contact 7 which is preferably formed of platinum. The rotating plate 1 carries on the other side of its axis a metallic projecting part 8 which supports a platinum electric screw contact piece 9 and also forms a guide 45 for an intermediate freely moving rod 10 which coordinates the movement of the two branches of the spring 4. 11 is a recess 50 for a carbon brush.

The apparatus works as follows:

In the position of the parts as illustrated the projection 5 is not affected by the cam 6 and the two electrodes 7 and 9 are in con-

tact. Current at this moment passes as is 55 desired between the plate 1 and the insulated piece 2. When rotated the projection 5 will strike the cam 6 which may be fixed or moving, thus deflecting one branch of the spring which will draw with it, through the 60 intermediary of the guided rod 10, the other branch of the spring carrying the electrode 7; the electrode 7 thus becomes separated from the electrode 9, and the current which was established will be broken; and so on 65 each time the projection 5 passes in front of the cam.

It will be understood that the drawing is only given by way of illustration and any other usual mechanical arrangements may be 70 employed. Thus an assemblage of cams may be rotated which will in turn act upon a fixed projection.

Claims:

1. In apparatus for making and breaking 75 an electric circuit, the combination of a yieldingly mounted control member, a cam-operated yieldingly mounted member, and a power transmitting element, intermediate said members for impressing the movement of one member upon the companion member for making and breaking the circuit.

2. In apparatus for making and breaking 80 an electric circuit, the combination of a revoluble support, a yieldingly mounted contact member and a yieldingly mounted contact-operating member both mounted in said support, and a power transmitting element intermediate said members for impressing the 85 movement of one of said members upon the other, and a cam in the path of said operating member for making and breaking the circuit.

3. In apparatus for making and breaking 90 an electric circuit, the combination of a revoluble support, a spring contact element and a contact operating spring element both mounted on said support, a thrust member intermediate said spring elements 95 for impressing the movement of one spring element upon the other and a cam in the path of the second named spring element for making and breaking the circuit.

4. In apparatus for making and breaking 100 an electric circuit, the combination of a revoluble support having a spring contact element and a contact operating spring

element provided with an insulating projection mounted thereon, a thrust member intermediate said spring elements for impressing the movement of one spring element upon the other element and a cam in the path of said insulating projection.

5 In testimony whereof I have signed this

specification in the presence of two subscribing witnesses.

JOSEPH BOUTEILLE.
